UNITED STATES PATENT OFFICE.

ADAM HEBERER, OF ALAMEDA, CALIFORNIA.

FEED-WATER PURIFIER.

SPECIFICATION forming part of Letters Patent No. 395,779, dated January 8, 1889.

Application filed February 23, 1888. Serial No. 265,045. (No model.)

To all whom it may concern:

Be it known that I, ADAM HEBERER, a citizen of the United States, residing in the city of Alameda, county of Alameda, and State of California, have invented certain new and useful Improvements in Feed-Water Purifiers for Steam-Boilers; and I do hereby declare that the following is a full, clear, and exact description of my invention, reference being had to the drawings which accompany and form a part of this specification.

My invention relates to improvements in purifying water for steam - generating purposes before introducing or feeding it into a boiler; and the same consists in an improved construction and combination of a water-heater in and with a steam-boiler, and in connection therewith a filtering and separating vessel or chamber, by the joint operation of which, as hereinafter more fully described, the water is first raised to a degree of temperature sufficient to induce separation of mineral and other matter in solution, and is afterward purified by being carried through a filtering-chamber before it is fed into the boiler. By means of suitable pipes with the necessary cocks and check-valves connection is made with the steam-space of the boiler and the boiler-pressure is used for cleaning out the apparatus.

The nature of these improvements and the manner in which I proceed to construct, apply, and operate the same are fully explained in the following description, in which the accompanying drawings are referred to by figures and letters.

Figure 1 represents my invention applied to a steam-boiler of the horizontal tubular kind, the shell of the boiler being shown in section; and the boiler-setting and other parts being omitted for the sake of clearness. The filter and the heads of the heating device in the boiler are also shown in section. Fig. 2 is a cross-section through one of the heads of the heater, and Fig. 3 a similar section through the opposite head. These two views are given on a larger scale. Fig. 4 is a similar view through one head of a heater of smaller capacity than the heater represented in Figs. 2 and 3, or which has a single return-passage.

Similar letters of reference indicate like parts in all the figures of the drawings.

A represents a boiler, in which X is the steam-space, and Y the water-space.

B B are tubes extending through the steam-space, and having both ends carried through the boiler to terminate in two heads or chambers, B' B², on the outside. The space within each one of these heads is divided by a partition, B³, which in the head B' or the one 60 having connection with the feed-pump is a solid partition, but in the opposite head has an opening or openings, b.

C is the pipe connecting the head B' with the feed-pump, and D is a steam-pipe leading 65 from the steam-drum or other part of the boiler to bring the boiler-pressure into the heater when it is desired to clean it. The pipes C and D are joined by a T-coupling to a common connecting-pipe, C^x, that is screwed 70 into the head B', and suitable stop-valves, Z Z, are placed in both pipes for letting in either water or steam.

E is a pipe connecting the other space or compartment in the head B' with the filter G. 75 This part of the apparatus is a steam-tight vessel divided by a perforated partition, G^x, into two compartments, x y, the upper one containing filtering material, G², that is laid upon the partition to a suitable depth, and 80 the lower one having connection through the pipe E, before mentioned, with the head B' of the heater. From the space x above the filtering media connection is made by a pipe, H, to the water-space of the boiler to be supplied. The filter is thus interposed in the length of the feed-water-supply pipe between the heater and the inlet into the boiler-space, so that after circulating through the pipes or passages of the heater the feed-water is 85 carried through the filter before entering the boiler-water. The pipes or passages of the heating device within the boiler have no direct communication with the boiler-space, and the feed-water is not delivered into the 90 boiler for steam-making purposes until it has passed through the filter.

In applying this device to a boiler of the horizontal type holes of suitable size to admit the pipes B are cut through the shell of 100 the boiler at both ends, and the pipes are of sufficient length to project outside the shell at both ends when set in position through the boiler-space. Over these projecting ends are fixed the heads or chambers B' B², with the 105 partition in each one setting between the ends of the pipes. To fix these heads in place, they should have flanges b², with holes for

bolts by which they can be secured against the boiler-shell.

The ends of these heads should be removable for purposes of cleaning out the chambers or removing and replacing the pipes B, or to facilitate inspection of the pipes and passages. By taking off the ends B⁴ of both heads the inside pipes or passages can be inspected for their entire length from either end 10 of the boiler. If one head is made a duplicate of the other, the connecting-pipes C and E may be changed from one end of the boiler to the other; or the connection of the feed-pump and the filtering device with the heater 15 can be made at either end, as most convenient. In such case the openings in the partition of that head to which the connections are made will be closed by plugs b⁵, provided for the purpose.

20 The filtering-chamber has a waste-pipe, I, leading from the bottom for carrying off the sediment and other matter when the filter is being cleaned out. The boiler-pressure can be used for this purpose at such time by shutting off the feed, closing the stop-valve W in the pipe E, and letting off the boiler-pressure back through the pipe H. The loop T in this pipe is provided for cutting out the check-valve V. This operation is intended to clean 25 the filtering medium in the chamber by reversing the travel of the water through it; but the sediment or precipitations collecting in the bottom of the chamber around the inlet-pipe may be blown off at any time by opening 30 the pipe to the atmosphere.

The capacity of the heating device may be enlarged by increasing the number of pipes, as shown in Figs. 2 and 3 of the drawings.

Having thus fully described my invention, 40 what I claim, and desire to secure by Letters Patent, is—

1. A feed-water-purifying apparatus consisting of a water-heating device located inside the boiler, by which the heat within the 45 steam-generating space is utilized for raising the temperature of the feed-water, said heating device consisting of the horizontal pipes or passages connected by the heads or chambers, arranged and constructed as set forth, a 50 filtering device located outside the boiler, and suitable pipes with valves connecting the heating device with the feed-pump and with the filtering device, and also the filtering device with the steam-generating space of the 55 boiler, whereby the feed-water is caused to pass through the heating device and then outside the boiler into and through the filtering device before being delivered into the boiler-water, substantially as described, for 60 operation as set forth.

2. In a feed-water heating and purifying apparatus for steam-boilers, a heating device located within the boiler and connected with the feed-pump outside, said heating device 65 consisting of the horizontal pipes connected by the heads or chambers, arranged and constructed as described, a conducting-pipe lead-

ing from said heater outside the boiler and adapted to deliver the feed-water therefrom into the boiler-water, and a filtering device interposed in the length of said pipe between the heater and the filter, in combination, substantially as described, the connections between feed-pump and heater and between filter and heater having the necessary valves 75 for controlling the feed-water, as set forth.

3. In combination with a steam-boiler, pipes or passages B, which extend through the steam-generating space of the boiler to the outside, the connecting heads or chambers B' B², by which said pipes or passages are made to form a return-passage, and suitable pipes by which one end of said return-passage is connected with the feed-pump and the other end with the water room or space 85 in the boiler, substantially as described.

4. The combination of water tubes or passages inside a boiler and extending to the outside through the shell thereof, and connecting heads or chambers B' B², having separate compartments, of which those in one head are in communication with each other through an opening or openings, b, and those in the other head have no direct connection, but are connected by suitable pipes or passages, the one with the feed-pump and the other with the water-room of the boiler, substantially as described.

5. In combination with a steam-boiler, water-heating tubes or passages B, extending through the boiler-space to the outside, the connecting heads or chambers B' B², by which said pipes are made to form a return-passage, a feed-water pipe connecting one end of said heater with the feed-pump, a pipe connecting the other end with a filtering-chamber outside the boiler having a filtering diaphragm or partition, a pipe connecting said filter with the water room or space of the boiler, and a blow-off or waste pipe leading 100 from the filtering-chamber, substantially as described, for operation as set forth.

6. A feed - water - purifying apparatus for steam-boilers, consisting of the water-heating tubes or passages leading into and out of the 105 boiler, the connecting heads or chambers B' B², having separate compartments, a feed-water-supply pipe, a steam-pipe, a filtering-chamber divided by a filtering diaphragm or partition, a pipe connecting the compartment on one side of the partition with the heating device in the boiler, and the water room or space within the boiler with the other compartment, a blow-off or waste pipe, and suitable valves in said pipes for controlling 110 the flow and circulation of the water directing the boiler-pressure through the apparatus, substantially as described, for operation as set forth.

In testimony that I claim the foregoing I 115 have hereunto set my hand and seal.
